CLAIM

The ornamental design for a beverage container, as shown and described.

DESCRIPTION

FIG. 1 is a front elevation view of a beverage container showing my new design;

FIG. 2 is a rear elevation view of the beverage container of FIG. 1;

FIG. 3 is a left side elevation view of the beverage container of FIG. 1;

FIG. 4 is a right side elevation view of the beverage container of FIG. 1;

FIG. 5 is a top view of the beverage container of FIG. 1;

FIG. 6 is a bottom view of the beverage container of FIG. 1;

FIG. 7 is a sectional view of the beverage container of FIG. 1; taken in the direction of line 7-7 on FIG. 5;

FIG. 8 is a sectional view of the beverage container of FIG. 1; taken in the direction of line 8-8 on FIG. 5; and,

FIG. 9 is a top perspective view of the beverage container of FIG. 1.

1 Claim, 5 Drawing Sheets
